SHEET DELIVERY MECHANISM FOR PRINTING PRESSES

Elbert Edwin Joel, Galveston, Tex., assignor of one-half to James H. Phipps and Charles B. Smith, Galveston County, Tex.

Application May 17, 1954, Serial No. 430,118

1 Claim. (Cl. 271—74)

My invention relates to improvements in suction sheet delivery mechanism for printing presses of the so-called Kluge type in which the sheets are delivered from the platen by suction arms.

The primary object of my invention is to provide the suction arms of such sheet delivery mechanism with extension suction sections swingable on the suction arms into set positions to pick up smaller pieces of printed stock than can be accomplished with the suction arms alone and which can be set to one side or the other so that they will not interfere with feeding of stock to the platen.

Another object is to provide suction extension sections for the above purpose attachable to the conventional suction delivery arms without alteration of the arms.

Other and subordinate objects together with the precise nature of my improvements will become readily apparent when the following description and claim are read with reference to the drawings accompanying and forming part of this specification.

In said drawings:

Figure 1 is a fragmentary view in perspective illustrating my improved extension suction sections applied to the suction delivery arms of the Kluge type printing press;

Figure 2 is a fragmentary view in perspective illustrating how the sheet delivery arms may be used with my extension suction sections thereon to deliver narrow sheets from the platen;

Figure 3 is an enlarged fragmentary view in longitudinal section taken on the line 3—3 of Figure 1; and

Figure 4 is an enlarged view in perspective of one of the extension suction sections detached.

Referring to the drawings by numerals, 1 designates generally a press of the Kluge type forming the subject matter of U. S. Letters Patent No. 2,088,377, and which has been illustrated fragmentally herein as sufficient to a proper understanding of the sheet delivery mechanism and my improvements thereon.

The sheet delivery mechanism C comprises an oscillating track 57 in the rear of the platen 12 pivoted at its rear end, as at 58, on a bracket 59 on the frame 12 of the press 1. A carriage 60 carrying a tubular suction support 61 reciprocates on the track 57 toward and from the platen 12. A pair of hollow suction delivery arms 62 are carried by the carriage 60 at opposite sides of the platen 12. Clamps 63 mount the delivery arms on the support 61 for lateral swinging adjustment thereon and bodily adjustment laterally of the platen also for longitudinal adjustment toward and from the platen 12 to position said arms 62 relative to sheets on the platen 12. The delivery arms 62 terminate in front down-turned suction tips 64. A suction hose 68 connects the support 61 to a suction source. A Y-fitting 67 on said support 61 and flexible hose 66 between said fitting and the rear ends of delivery arms 62 connect said arms 62 to said support.

2

The platen 12 rocks on trunnions 24 from a closed to an open position shown in the drawings. Sheet grippers 84 of bar form are carried by a gripper bar 85 pivoted on the platen 12 at the front edge thereof, as at 86, for vertical swinging to release a printed sheet S on the platen 12 when the platen is rocked into fully open position.

Arm 88, roller 89, quadrant 91, roller 93, spring 95 and cam 94 form parts of the sheet gripper operating mechanism, shaft 23, arms 29 form part of the operating mechanism for the printing bed, not shown, and link 18 forms part of form roller operating mechanism, all of which need merely be mentioned in passing since these mechanisms are fully disclosed in the previously mentioned patent to which reference may be had for a complete understanding of this press.

As the platen 12 is rocked into its fully open position, the carriage is moved forwardly on the track 57 to move the delivery arms 67 over the front edge of the platen 12, the track 57 is rocked to swing the support 61 and delivery arms downwardly from the normal raised position, not shown, and the front ends of the delivery arms 64 are thus positioned for suction delivery of a sheet S off the platen after which said carriage 60 is moved rearwardly for delivery of the sheet S and said track 57 rocked to swing said arms upwardly to normal position. The arm 71 and link 70 form part of the carriage moving means. Reference to the beforementioned patent may be had for further disclosure of the carriage moving means and for the track oscillating means.

According to my invention a pair of tubular extension suction sections 100 are provided on the suction delivery arms 62 which are formed with front down-turned sheet gripping suction grip ends 101 preferably enlarged. The suction sections 100 each include attaching means comprising a vertical cup shaped adapter 102 on its rear end from one side of which the section extends having an external rim flange 103. A gland nut 104 threaded onto the suction tip 64 of the associated suction arm 62 and underlying the flange 103 rotatably attaches the suction section to its suction arm 100 for lateral swinging thereon. A gasket 105 in the gland nut 104 between the suction tip 64 and adapter 102 forms an air-tight seal between said adapter 102 and suction arm 62.

As shown in Figure 1, the extension suction sections 100 may be used to grip the work sheet A at the front edge of the platen 12 in the usual manner by adjusting the suction delivery arms 62 longitudinally rearwardly in the clamps 63. However, and as shown in Figure 2, by adjusting the suction delivery arms 62 forwardly longitudinally in the clamps 63, the extension suction sections 100 may be used for delivering narrow sheets S, or cards, from the platen 12 when placed against the usual rear or lower platen gauges 40. Obviously, the extension suction sections may be swung laterally so that the same will not interfere with the usual sheet feeding means, not shown, of such presses.

The foregoing will, it is believed, suffice to impart a clear understanding of my invention without further explanation.

Manifestly, the invention may be modified without departing from the inventive concept, and right is herein reserved to modifications thereof falling within the scope of the appended claim.

What is claimed is:

A sheet delivery mechanism for use in a printing press comprising a pair of movable suction delivery arms, said arms being laterally, longitudinally and angularly adjustably mounted on a tubular support, carriage means

supporting said support for oscillatory movement whereby the arms are moved toward and away from the platen of the printing press, each of said arms having a perpendicularly disposed downturned suction tip on the free end thereof, a downwardly extending adaptor rotatably connected to each suction tip and having a closed lower end, said adaptor having an externally flanged upper end, an internally flanged nut rotatably securing the upper end of the adaptor to the suction tip, a disc seal disposed between the upper end of the adaptor and the suction tip, a laterally extending tubular extension rigid with and communicating with said adaptor adjacent the bottom thereof for swinging movement in a plane generally parallel to the horizontal plane of the arms about an axis defined by the longitudinal axis of the downturned suction tip and adaptor, each of said extensions terminating in downturned suction grip ends generally parallel to the downturned tips on said delivery arms for delivery of narrow sheets onto the platen adjacent the edge thereof remote from said support, the swing-

ing movement of said extensions about the axis of rotation of the adaptor facilitating variation in the relationship between the platen and the grip ends with the extensions forming a longitudinal prolongation of the arms capable of arcuate swinging movement thereby extending the effective reach of the arms in any angular direction in a plane parallel with the plane of the arms whereby the unobstructed area between the grip ends is provided with a greater variation than the unobstructed area between the suction tips on the delivery arms.
